UNITED STATES PATENT OFFICE.

SHERMAN L. BOLES, OF SAN FRANCISCO, CALIFORNIA.

ADJUSTABLE HEAD FOR GOLF CLUBS.

Application filed July 7, 1926. Serial No. 120,899.

My invention relates to improvements in golf clubs, having adjustable heads, and it consists of a combination, construction, and arrangement, hereinafter described and 5 claimed.

An object of my invention is to provide a golf club having an adjustable head, in which the parts are so arranged as to have the force of the impact of the golf ball 10 upon the blade tend to tighten the parts for more rigidly securing the parts together.

A further object of my invention is to provide a device of the type described, in 15 which the blade may be adjusted at various angles, or may be entirely removed and a new blade substituted therefor.

Other objects and advantages will appear in the following specification, and the novel 20 features of the device will be more particularly pointed out in the appended claims.

My invention is illustrated in the accompanying drawing forming a part of this 25 application in which,

Figure 1 is a vertical section through the device.

Figure 2 is a front elevation of the device and,

Figure 3 is a view showing a portion of 30 the locking pin.

Figure 4 is a top plan view of a modified form of the device.

Figure 5 is an enlarged detail of parts shown in Figure 1.

In carrying out my invention I provide 35 a ferrule which is designed to receive the handle 2.

The ferrule has a reduced tubular portion 3 which receives a screw 4. The screw 40 4 has a left hand thread for a purpose hereinafter described. A tubular casing 5 is rotatably mounted upon the outside of the portion 3 and has its end 6 crimped into a groove 7, whereby the casing 5 is rotatably 45 secured to the ferrule 1.

A blade 9 has a dove-tailed slot 8 therein for receiving a projection 10, carried by the screw 4. The projection 10 permits the blade 9 to be swung into the desired angle. 50 It will be noted in Figure 2 that the projection 10 has inclined walls 11 limiting the movement of the blade 9. The walls 8 of the blade contact with the walls 11 when the blade has been swung through a pre-determined distance.

This means for securing the blade in position comprises a serrated edge 12 in the blade 9 engaging with a serrated edge 13 on the casing 5. The edges 12 and 13 are arcuate shape and tapered for adding greater strength to the device. The edge 13 has a groove 14 which prevents the binding of the blade in the casing when the screw 4 is released. 60

From the foregoing description of the 65 various parts of the device, the operation thereof may be readily understood. To secure the blade 9 in place, the blade is first mounted upon the projection 10 and then the screw 4 is inserted into portion 3. A 70 rotation of the handle 2 to the left will draw the screw into place and will cause the serrated portions 12 and 13 to mesh.

To adjust the blade 9 to the desired angle it is merely necessary to insert the blade in 75 the palm of the left hand and then with the right hand make a one-half turn of the handle 2 to the right. This will release the blade 9 sufficiently to permit the blade to be swung into the desired angle. The casing 5 is provided with graduations 14' and the blade 9 is provided with a mark 15 for this purpose. 80

It will be noted that the head of the golf club will tend to pivot the casing 5 in a 85 direction for tightening the screw 4. Figure 1 shows that the blade 9 may be of various shapes so as to extend at different angles in the manner shown. Any of the blades 9 may be delicately adjusted to the desired 90 loft.

It is further to be noted that the concentration mass is at the desired point regardless of the angle into which the head 9 is swung. This construction causes the 95 club to have the same feel at all the positions which the head 9 may take with respect to the handle 2. This permits the golfer to have his mind clear to measure the force of the blow, and the direction of the 100 shot. Due to the fact that the same club is being used, the other values remain the same in all cases.

In Figure 4 I show a slightly modified 105 form of the device. The blade 25 is bent at 26 for causing the angle formed between the longitudinal axis of the shaft and the lie, to be increased as the loft is increased. Of course the same is true with the form 110 of the device shown in Figures 1 and 2, but

the angle formed by the shaft and blade will not vary so greatly, as the form of the device shown in Figure 4.

I claim:

- 5 1. A golf club comprising a handle, a casing carried by said handle, a left handed screw receivable in said casing, said screw having a projection, a blade having a recess for receiving said projection whereby
10 said blade is secured to said screw, said blade being pivotally mounted on said projection, cooperating means carried by said casing and said blade for securing said blade in angular position with respect to
15 said casing, said screw when moved into position bringing the means of said casing and of said blade into abutting relation, whereby said blade is secured in place.

2. A golf club comprising a handle, a blade having a wedge shaped recess therein, 20 a left handed screw removably secured to said handle, a wedge shaped projection carried by said screw and being removably receivable in said recess.

3. A golf club comprising a handle, a 25 blade having a wedge shaped recess therein, a left handed screw removably secured to said handle, a wedge shaped projection carried by said screw and being removably receivable in said recess, and means for locking said blade in angular position with respect to said handle.

In testimony whereof I have affixed my signature.

SHERMAN L. BOLES.
